(57) **CLAIM**

The ornamental design for a portable coordinate measurement machine, as shown and described.

DESCRIPTION

FIG. 1 is a perspective view of a portable coordinate measurement machine showing our new design in accordance with a fourth embodiment of the invention;

FIG. 2 is a front view of the portable coordinate measurement machine as shown in FIG. 1;

FIG. 3 is a rear view of the portable coordinate measurement machine as shown in FIG. 1;

FIG. 4 is a left side view of the portable coordinate measurement machine as shown in FIG. 1;

FIG. 5 is a right side view of the portable coordinate measurement machine as shown in FIG. 1;

FIG. 6 is a top view of the portable coordinate measurement machine as shown in FIG. 1;

FIG. 7 is a bottom view of the portable coordinate measurement machine as shown in FIG. 1;

FIG. 8 is a perspective view of a portable coordinate measurement machine showing our new design in accordance with a fifth embodiment of the invention;

FIG. 9 is a front view of the portable coordinate measurement machine as shown in FIG. 8;

FIG. 10 is a rear view of the portable coordinate measurement machine as shown in FIG. 8;

FIG. 11 is a left side view of the portable coordinate measurement machine as shown in FIG. 8;

FIG. 12 is a right side view of the portable coordinate measurement machine as shown in FIG. 8;

FIG. 13 is a top view of the portable coordinate measurement machine as shown in FIG. 8; and,

FIG. 14 is a bottom view of the portable coordinate measurement machine as shown in FIG. 8.
